Inventor.

Stephen Wilks.

STEPHEN WILKS, OF CHICAGO, ILLINOIS.

Letters Patent No. 83,679, dated November 3, 1868; antedated October 17, 1868.

IMPROVEMENT IN COOKING-RANGES.

The Schedule referred to in these Letters Patent and making part of the same.

To all whom it may concern:

Be it known that I, STEPHEN WILKS, of Chicago, Cook county, and State of Illinois, have invented a new and improved Cooking-Range, especially adapted for use in sleeping-cars; and I do hereby declare that the following is a full and exact description thereof, reference being had to the accompanying drawings, and to the letters of reference marked thereon, which form a part of this specification, in which—

Figure 1 represents a front elevation of my improved cooking-range.

Figure 2 represents a side elevation, with part of the casing torn away, exposing to view the arrangement of water-pipes and kettle.

Figure 3 is a vertical, central, and side section.

Figure 4 is a view of kettle, showing pipes connecting it to the water-back.

The nature of my invention consists in constructing a cooking-range in such peculiar form and combination as to particularly adapt it for use in railway sleeping-cars, and other places where space is limited and cooking desirable.

To enable those skilled in the art to make and use my invention, I will describe its construction and operation.

A is the fire-place. The heat passes, in the direction of the arrows, around the oven B, underneath oven C, and out through flue W.

Y is a broiler, hinged at y, so that it may be turned back, and out of the way, when not in use.

J is the fire-door, hinged at j, and supported by the

quadrants, I, when opened to a horizontal plane; and when in this position, it constitutes an extremely convenient table.

B is the bake-oven, and

C, the warming-oven, for plates, &c.

D is ash-pan, arranged in the usual manner.

E is the coal-cell or fuel-receptacle, arranged at the base, and within the casings of the range.

F is stationary boiler.

O is cold-water pipe.

Q and U are pipes leading to water-back V, in rear side of fire-place.

Hot water passes back to the boiler F through pipe S.

T is a waste-pipe, leading to the outside of the apartment, through which the water in boiler F and kettle H may be drawn off, when desired, by means of cocks M and N.

Kettle H is connected to water-back V', in front part of fire-place, as shown in fig. 4.

Z is a space, partitioned at the side of fire-place A, forming an oven, in which tea and coffee may be kept hot.

Having thus fully described my invention,

What I claim as new, and desire to secure by Letters Patent of the United States, is—

The arrangement of the several parts constituting my said range, as above specified and shown.

STEPHEN WILKS.
